SPRAYING DEVICE FOR PAPER MACHINES

Arthur E. Broughton, Glens Falls, N. Y.

Application April 14, 1939, Serial No. 267,772

1 Claim. (Cl. 92—50)

This invention relates to showers for paper making machines and other machines where showers are required.

It is one of the objects of the present invention to provide a novel and improved shower for paper making machines and the like which is compact, light in weight, inexpensive and efficient and can be installed readily on such machines.

Another object is to provide a novel and improved reciprocating shower which includes no hoses or flexible conduits for supplying the fluid to the shower head.

Another object is to provide a novel and improved reciprocating shower which can be extended across the member to be sprayed and which can be supported solely from one side of the member without support at the other side thereof.

Another object is to provide a reciprocating shower which can be supported at one end of a rotary cylindrical screen having one closed end and one open end and which can be extended through the open end of the screen into the interior thereof to produce a reciprocating jet spray that will work against the inner side of the screen.

Another important object of the invention is to provide a reciprocating shower which can be substituted for existing stationary showers on paper making machines and will greatly economize on the quantity of water employed and will be highly efficient in action.

A more specific object of the invention is to provide a shower having a rigid and stationary water supply pipe, a sleeve-like spray head slidably mounted on the supply pipe and packed relative thereto, the stationary supply pipe communicating with the sleeve-like spray head and means for reciprocating the spray head on the supply pipe.

The objects and advantages of the invention will more fully appear from the following description made in connection with the accompanying drawing, wherein like reference characters refer to the same or similar parts throughout the various views, and in which,

Fig. 1 is a vertical longitudinal section taken through the left hand portion of a shower embodying the invention and the left hand portion of a rotary cylindrical screen in conjunction with which the shower is used;

Fig. 2 is a similar section through the right hand portion of the screen;

Fig. 3 is a similar section through the right hand portion of the shower, Figs. 2 and 3 being so inter-related as to show the relative positioning of the right hand portions of the shower and screen;

Fig. 4 is a view in side elevation of the right

hand end portion of the shower shown in Fig. 3;

Fig. 5 is a view in front elevation looking toward the left hand end of the structure shown in Fig. 1; and

Fig. 6 is a vertical section taken on the line 6—6 of Fig. 1 as indicated by the arrows.

In accordance with the embodiment of the invention illustrated in Figs. 1, 2, 3, 4, 5 and 6, portions of a rotary screen 10 of the type commonly employed in paper making machines for removing the lumps and clotted masses from the watered pulp prior to its passage to the Fourdrinier wire, are shown. This screen 10 includes a closed end 10a which is fixed to the shaft (not illustrated) that rotates the screen and it further includes a ring-like head 10b having an opening 10e therein and forming an open end for the screen. The foraminous screen proper which acts as a strainer and is designated by the numeral 10c is cylindrical and extends between the closed end 10a and the head 10b. This screen proper 10c is provided with a multiplicity of very fine slots 10d running circumferentially of the screen and spaced longitudinally of the screen from each other, these slots being of rather short length and being interrupted by solid portions of the screen. In the drawing in Figs. 1 and 2 the width of the slots is greatly exaggerated as is also the spacing between the slots. The screen 10 works within a trough, not illustrated, and the watered pulp is fed onto the exterior of the screen to pass through the slots 10d into the interior thereof and the screen acts as a strainer to prevent the passage of lumps, clots, etc. through the screen.

In connection with such a screen, as screen 10 illustrated, it is now the common paper mill practice to utilize a stationary shower which runs into the screen through the open end thereof and sprays on to the screen from the inner side thereof to remove any material that may clog the slots 10d of the screen. With such stationary showers it is the common practice to employ from between 3,000 to 6,000 gallons of water per hour to clean the screen.

The shower of the present invention is used to replace the old type of stationary shower and to reduce the water consumption of from 3,000 to 5,000 gallons per hour to in the neighborhood of 100 gallons per hour while producing comparable or better cleaning results.

As shown in Figs. 1 and 4, a suitable supporting structure is provided close to the open end of the screen 10 but out of the way of the screen. This supporting structure illustrated includes a bow 11 of angle bar construction supported in any suitable manner as from the bottom of the trough within which the screen 10 works, and a cross bar 12 which runs across the bow 11 in

downwardly spaced relation from the top thereof. Secured as by bolts 13 and 14 to the bow 11 and cross bar 12 is a mounting bracket 15 for my shower.

This mounting bracket 15 has two horizontal openings therethrough, in the upper one of which a water supply pipe 16 is mounted. As shown, this supply pipe 16 includes a short horizontal section 16a mounted in the bracket 15 and a longer horizontal section 16b closed at its end remote from the bracket 15 by a plug 17. The supply pipe 16 runs into the screen 10 through the open end of the same and extends to a point close to the closed end 10a of the screen. As shown by the relative positioning between screen head 10a and plug 17 in the conjoint views Figs. 2 and 3, the supply pipe is located at a level spaced from but quite close to the top of the screen. A water feed pipe 18, connecting with any suitable source of water supply, connects to a strainer 19 and this strainer in turn connects with an elbow 20 attached to the outer end of the supply pipe 16.

A spray head 21 is mounted for sliding reciprocating movement on the section 16b of the supply pipe 16. This spray head consists of a sleeve-like pipe carrying a plurality of spaced spray nozzles 22 which are directed upwardly toward the top of the screen 10. The two ends of the spray head 21 are closed by ring-like plugs 23 carrying packing 24 so that while reciprocation of the spray head 21 is permitted relative to the supply pipe 16, water tight connections are made between the ends of the spray head and the section 16b of the supply pipe at all times. Fluid communication between the supply pipe 16 and the spray head 21 is afforded by means of openings 25 in the section 16b of the supply pipe, these openings, of course, being located between the two plugs 23 within the limits of reciprocation of the spray head 21. In order to permit spraying of the extreme right hand end portion of the screen and still to permit the right hand end of the supply pipe 16 to be spaced somewhat to the left of the closed end 10a of the screen, an auxiliary pipe 26 carrying spray nozzles 27 is connected to the right hand end portion of the spray head 21 to extend beyond the right hand plug 23 of the spray head.

The supporting bracket 15 carries in the lower opening thereof a supporting tube 28. This tube is preferably made in two sections 28a and 28b and the inner section extends into the screen 10 and carries at its inner end a securing bracket 29 which is attached to the inner end of the supply pipe 16 as by means of a pin 30. The supporting bracket 15 and tube 28 thus form the sole support for the supply pipe 16 and the spray head 21 and, of course, the bracket 15 is located at one end of the screen 10 so that while the supply pipe and spray head are very strongly supported, the supporting structure does not interfere with the movement of the screen 10 and no alterations must be made in the screen to install the present shower.

Carried by the outer end of the tube 28 is a fluid pressure motor 31. This fluid pressure motor includes a piston 31a working within a cylinder 31b and the piston is reciprocated in the cylinder preferably by air pressure. Inasmuch as any small compact motor could be substituted for the motor 31 to cause reciprocation of the parts, further description of the motor 31 is

thought unnecessary here. The piston 31a is connected to a piston rod 32 which runs through a packing gland 33 in the end of the motor 31 connected to the tube 28. The free end of the piston rod 32 is connected by a universal joint 34 to a rod 35 working within the tube 28 and mounted for reciprocation therein on a ring bearing 36 carried by the tube 28. The section 28b of the tube 28 is provided at its upper part near its inner end with a slot 37 of a length slightly greater than the length of travel of the piston 31a and piston rod 32. Secured to the inner end of the spray head 21 is an arm 38 which projects downwardly from the spray head through the slot 37 into the tube 28 and is connected to the inner end of the rod 35. With this construction it will be seen that as the motor 31 reciprocates the piston rod 32 the rod 35 will be similarly reciprocated and this rod being connected to the spray head 21 through the arm 38, the spray head will be reciprocated back and forth on the rigid supply tube 16.

When a shower is in operation water furnished by the pipe 18 will run into the supply pipe 16 and thence through the openings 25 into the sleeve-like spray head 21 to be ejected from the spray nozzles 22 in fine needle-like sprays which strike the inner surface of the screen 10. The reciprocation of the spray head 21 will cause the same to move longitudinally of the axis of rotation of the screen 10 and accordingly the spray jets will move transversely of the screen slots 10d while the screen is being rotated. These spray jets due to the reciprocation of the spray head, will strike the slots of the screen at varying angles, and will efficiently remove any clots or other obstructions in the slots 10d. By reason of the fact that the spray head is under reciprocation at all times, rather than stationary, but a small quantity of water is required to keep the screen clean in comparison to the large quantity of water that has customarily been used for the same purpose in connection with the usual stationary showers.

It will be seen that a highly efficient reciprocating shower has been provided to operate for the purposes intended.

It will, of course, be understood that various changes may be made in the form, details, arrangement and proportions of the various parts without departure from the scope of the invention which generally stated consists in the matter shown and described and set forth in the appended claim.

What is claimed is:

55. In a paper making machine, a rotary cylindrical screen having one closed end and one open end and through which watered pulp passes from the exterior of the screen to the interior thereof, a fixed water supply tube extending into said screen from the open end thereof, a tubular apertured spray head mounted for reciprocation within said screen on said water supply tube and having its ends packed relative to said tube, said tube having communication with said spray head between the packed ends thereof, means for reciprocating said spray head, stationary means for supplying water to said tube, and fixed means adjacent the open end of said screen for solely supporting said tube and said means for reciprocating said spray head.

ARTHUR E. BROUGHTON.
